G. L. Kennedy,
Attorney.

UNITED STATES PATENT OFFICE.

CRENO P. BETTENGA, OF PARKERSBURG, IOWA.

WASHING-MACHINE.

1,326,636.

Specification of Letters Patent. Patented Dec. 30, 1919.

Application filed January 17, 1919. Serial No. 271,560.

To all whom it may concern:

Be it known that I, CRENO P. BETTENGA, a citizen of the United States of America, and a resident of Parkersburg, Butler county, Iowa, have invented certain new and useful Improvements in Washing-Machines, of which the following is a specification.

My invention relates to improvements in washing-machines, and the objects of my improvements are, first, to provide in a tub or liquid container a rocking clothes receptacle, permeable to the liquid in the container, and deformable when rocked to impose 10 different movements to its contents, and second, to shape the bottom of the container to a form suitable to coact with the deformable receptacle in various ways in operating upon the contents of the latter. 15 These objects I have accomplished by the means which are hereinafter described and claimed, and which are illustrated in the accompanying drawings, in which Figures 20 1 and 2 are respectively cross and longitudinal sections of my improved washing machine, taken on the broken lines 1—1 and 2—2, respectively, of said Figs. 2 and 1, looking in the directions indicated by the arrows. 25

Similar numerals of reference denote corresponding parts throughout the several views.

I employ a tub or liquid container 1 of hollow cubicular shape, supported on legs 35 and provided with a top closure 2, hinged thereto on hinges 3. The bottom 4 of the container is medially upwardly ridged longitudinally, with the oppositely directed slopes leading to narrow longitudinal troughs 6 provided to collect slime or dirt. The numeral 9 denotes a cross-pipe positioned under the bottom 4 medially, having upwardly-bent ends which communicate with the troughs 6. A short depending tube 40 leads from the middle of the pipe 9 to a spigot or valve-chamber 10. The bottom of each trough 6 is closed by a strip 8, between drop-pieces 7 and the walls of the container. The apex or ridge of the bottom 4 is preferably somewhat flattened, as by the insertion of a medial longitudinal strip 5.

I have provided within said container a clothes-receptacle, permeable to the liquid in the container in which it is preferably 45 half immersed. This receptacle is composed of a plurality of movable parts forming

pivotaly connected bottom, side and end walls, the top being open. The bottom and side walls may be of any kind, whether perforated or imperforated, but, as shown, the bottom comprises spaced longitudinal slats 14 fixed to end-strips or cross-slats 15, while the side walls are composed of spaced longitudinal slats 18 fixed by screws 25 to end standards 16, preferably of rectangular cross-section. These side-walls and bottom are essentially slatted or intersticed panels which are hingedly connected to permit body deformation of the receptacle. The connecting-means consist of a plurality of spaced slats 15, horizontally parallel to the first-mentioned bottom end slats, all the slats being pivoted at their opposite ends to the end-standards 16 on headed pins 17. The lowermost slats 15 are rectangularly notched at 18 in the middles of their lower edges to receive removably a longitudinal beam 11 of rectangular cross-section, but whose ends are shaped cylindrically to provide pintles 12, said beam and its pintles 20 constituting a rock-shaft operable as follows. Said pintles are mounted in bearings 27 and 28 of said container, the latter being a stuffing-box, and an arm 26 is fixed on the outer end of said pintle 12. 85

The numeral 19 denotes a pair of like vertically-disposed boards or standards placed medially against the inner faces of the end walls of the containers and secured detachably thereto by bolts 22 and 24, of which the upper bolts 22 are seated in end notches 21 of said boards. The numeral 20 denotes pintles extending from said boards 19 through the middles of the uppermost end-slats 15, pivotally. The squared rock shaft 90 11 is positioned flatly and longitudinally, along and upon the flat medial portion 5 of the rigid bottom 4.

When the shaft 11 is rocked to and fro by means of the rock-arm 26, or by any other means, rocking movements are communicated to all the end-slats 15 with said bottom slats 14. However, as the top end-slats 15 are medially pivoted to the fixed standards 19 on said pintles 20, the corner standards 16 and the slatted side-walls cannot rock but have up and down approximately vertical movements, whereby the rectangular receptacle is distorted or changed into variable rhombic shapes, alternately, in opposite directions. This causes clothes in 95 said receptacle to slide to and fro across

it, and the liquid in the container is forced through the permeable walls and bottom of the receptacle, into the convolutions of the clothes, as the receptacle dips and is alternately elevated from the liquid, whereby all surfaces of the clothes are washed and rubbed against the slats of the bottom and walls. The ridging of bottom 4 results in diminishing the quantity of liquid needed 10 to properly immerse the receptacle in its downward movements, and the latter can move as far as the slopes of the bottom, while rocking. This stirs up the liquid, keeps it of homogeneous composition and 15 prevents settling of the soapy component.

The receptacle may be readily removed from the container by detaching the pintles 20 and lifting it from the squared shaft 11 to which it is not fastened.

20 Having described my invention, what I claim as new, and desire to secure by Letters Patent, is:

1. A washing-machine, comprising a liquid container having an upwardly-ridged bottom, and a receptacle within said container having its bottom pivotally mounted at the apex of said ridged bottom to rock to and fro.

2. A washing-machine, comprising a liquid container having an upwardly-ridged bottom, a receptacle within said container

having its bottom pivoted medially mounted immediately above the apex of said ridged bottom to rock to and fro limited by the slopes thereof, and means for rocking 35 said receptacle movably connected to said container.

3. A washing-machine, comprising a liquid container, having an upwardly ridged bottom, a rock-shaft mounted in said container longitudinally above the ridge of said bottom, and a receptacle in said container having its bottom mounted removably on said rock-shaft to rock therewith, parts of said receptacle being pivotally connected 45 together, of which the upper part is pivotally mounted on the container.

4. In a washing-machine, a liquid container having a bottom sloped downwardly outwardly to both sides of a medial longitudinal line, a rock-shaft mounted along the apical ridge of said bottom, an intersticed clothes-receptacle secured removably upon said rock-shaft, said receptacle being formed of pivotally-connected elements, 55 standards removably erected in the ends of said container, and means for pivotally connecting the upper end parts of said receptacle to said standards.

Signed at Waterloo, Iowa, this 30th day 60 of Dec., 1918.

CRENO P. BETTENGA.
